(57) **CLAIM**

The ornamental design for a UV-light disinfection robot light assembly tower cap, as shown and described.

DESCRIPTION

FIG. 1 shows a top left-side front perspective view of an embodiment of the UV-light disinfection robot light assembly tower cap of our new design, disclaiming an enclosure for an automatic guided vehicle assembly supporting the UV-light disinfection robot light assembly tower cap and a lighting tower assembly mounted thereunder;

FIG. 2 shows a front elevation view thereof;

FIG. 3 shows a right-side elevation view thereof;

FIG. 4 shows a rear elevation view thereof;

FIG. 5 shows a left-side elevation view thereof;

FIG. 6 shows a top plan view thereof;

FIG. 7 shows a top right-side rear perspective view thereof;

FIG. 8 shows a bottom left-side front perspective view of the UV-light disinfection robot light assembly tower cap of our new design opposite that of FIG. 7, disclaiming the enclosure for the automatic guided vehicle assembly and the lighting tower assembly disposed thereunder; and,

FIG. 9 shows a bottom right-side rear perspective view of the embodiment of the UV-light disinfection robot light assembly tower cap of our new design opposite that of FIG. 1, the embodiment disclaiming the enclosure for the automatic guided vehicle assembly and the lighting tower assembly disposed thereunder.

The broken or evenly-dashed lines are included to show structure of the robot that form no part of the claimed design.

1 Claim, 9 Drawing Sheets
